UNITED STATES PATENT OFFICE.

JULIUS JUDELSON, OF NEW YORK, N. Y.

DRIER.

Application filed August 1, 1923. Serial No. 655,015.

To all whom it may concern:

Be it known that I, JULIUS JUDELSON, citizen of the United States, residing at 1197 Grand Concourse, in the city of New York, in the county of Bronx and State of New York, have invented certain new and useful Improvements in Driers, of which the following is a specification.

This invention relates to improvements in driers. More particularly it is directed to a drier of the character described adapted for use in private dwelling houses where the driers ordinarily used have a single drying compartment.

One object thereof is to provide a drier of the character and for the purpose described with an improved and highly efficient heating apparatus for heating the air in the drying compartment, and so constructed and arranged as to prevent any of the gases or injurious fumes from the burners from coming into contact with the articles or materials being dried.

A further object is to provide a drying apparatus of the character described which shall be comparatively simple in construction and economical and efficient in operation to a high degree.

Other objects of this invention will in part be obvious and in part hereinafter pointed out.

Certain features herein shown and described are shown, described and claimed in my co-pending application Serial No. 654, 285 362, filed in the United States Patent Office on the 28th of July, 1923, and accordingly not claimed herein.

With the above exception the invention accordingly consists in the features of construction, combinations of elements and arrangement of parts which will be exemplified in the construction hereinafter described and of which the scope of application will be indicated in the following claims.

In the accompanying drawings, in which is shown one of the various possible illustrative embodiments of this invention,

Figure 1 is a view in vertical section through a drier casing or cabinet, showing my improved heater therein, said heater

being mainly in elevation but partly in section, the view being taken on the staggered line 1—1 of Figure 2.

Figure 2 is a sectional plan view corresponding to Figure 1.

Figure 3 is a view in transverse section on the line 3—3 of Figure 2.

Figure 4 is a view in transverse section on the line 4—4 of Figure 1.

Referring in detail to the drawing,

1 represents the drying cabinet which may be of any desired suitable construction.

In the bottom of the cabinet I provide feet 5 or other means to support a burner casing 2, and a substantially horizontal flue 65 3, the latter having the forward end thereof closed and extending into the burner casing. Perforations 3' are provided in the wall of the flue 3 within the said casing.

The rear or inner end of the flue 3 communicates with a pair of flues 4, the latter having their forward ends open and being secured in openings in the wall of the burner casing and disposed above the flue 3 to either side thereof.

Within the cabinet and preferably at the rear thereof, I provide a relatively wide box 6 communicating at its central upper portion with a tapering outlet 7, which communicates with a chimney 8. The box 6 is 80 perforated preferably in its front and bottom as shown at 6'.

A pipe 9, preferably of smaller diameter than flues 3 and 4, is positioned between the flues 4, and at its inlet end projects through 85 the rear wall of the burner casing 2, and thence downwardly to the top of the flue 3 where it is secured to the latter and has open communication therewith.

The rear end of pipe 9 projects upwardly 90 through the central portion of box 6 and terminates in the outlet portion 7; so that the draft through the chimney induces a draft or circulation through the pipe 9.

The forward end of the burner casing is 95 positioned within an opening in a front partition 10, and is of approximately V-shape in plan so as to divide the casing into two burner spaces in each of which a burner 11 is located. These burners are 100

shown as gas burners extending longitudinally within the casing and having a gas supply pipe 12 with suitable cocks 13; but obviously any suitable construction of burner or any suitable fuel may be employed, and I do not limit myself to the particular construction of burner nor to the fuel described.

10 Above each burner 11, a deflector 14 is provided, preferably of inverted V-shaped cross-section to throw the heat outwardly and also to direct the heat toward the inlet ends of flues 3.

15 The deflectors 14 may be supported in any suitable manner. In the form shown in the drawing they are shown secured to brackets 15 fixed to platforms 16 on which the burners are mounted.

20 The forward or front wall of the burner casing 2 is provided with perforated doors 17 in proximity to each burner 11, and these doors may be damper-controlled in any approved manner to admit air to the system, as may be desired.

25 The flues 4 are disposed above and to opposite sides of the flue 3 and directly communicate therewith at their inner ends. The union or coupling of the flues 4 with the flue 3 is in the form of a Y-connection 18, and

30 the pipe 9 in order to lie between the flues 4 and above the flue 3 passes through this Y-connection 18 as clearly shown in Figure 4, so that said pipe is heated to high degree by radiation from the flues 3 and 4, as well as by direct contact with the heated air.

35 The operation is as follows:—

The air heated in cabinet 2 flows through the flues 4, thence through the Y-connection 18 and through flue 3 back to chamber 2.

40 A portion of this air escapes through pipe 9 and is discharged into the outlet 7 of box 6. The air within the chamber or cabinet becomes heated by radiation from the walls of the burner casing 2, the flues 3 and 4 and from pipe 9, and is drawn through the perforations of box 6 up the chimney 8. The moisture is thus rapidly evaporated from the articles in the cabinet and the maximum results are obtained from the heat of the burners.

45 It will thus be seen that there is provided a device in which the several objects of this invention are achieved and which is well adapted to meet the conditions of practical use.

50 As various possible embodiments might be made of the above invention and as various changes might be made in the embodiment above set forth, it is to be understood that all matter herein set forth or shown in the accompanying drawings is to be interpreted as illustrative and not in a limiting sense.

55 Having thus described my invention I claim as new and desire to secure by Letters Patent,

1. A heater for driers and the like, comprising a burner casing, a heating element in the casing, a flue communicating at one end with the casing, a return flue communicating with the first mentioned flue and the casing, and an outlet pipe located adjacent said flues and communicating with the return flue in the burner casing. 70

2. A heater for driers and the like, comprising a burner casing, a heating element 75 in the casing, a flue communicating at one end with the upper portion of the casing, a return flue communicating with the first mentioned flue and projecting into the casing, and an outlet pipe located adjacent said 80 flues and communicating with the return flue in the burner casing.

3. A heater for driers and the like, comprising a burner casing, a heating element in the casing, a flue communicating at one 85 end with the upper portion of the casing, a return flue communicating with the first mentioned flue and projecting into the casing, an outlet pipe located adjacent said 90 flues and communicating with the return flue in the burner casing, said return flue having the end thereof projecting into the casing closed, the projecting portion thereof being perforated.

4. A heater for driers and the like, comprising a burner casing, a heating element in the casing, a flue communicating at one end with the casing, a return flue communicating with the first mentioned flue and the casing, and an outlet pipe located adjacent 100 said flues and communicating with the return flue in the burner casing, said outlet pipe extending through said flues at their point of communication with each other. 105

5. A heater for driers and the like, comprising a burner casing, a heating element in the casing including a burner, a flue communicating at one end with the casing, a return flue communicating with the first mentioned flue and the casing, an outlet pipe 110 located adjacent to said flues and communicating with the return flue in the burner casing, and a deflector disposed above said burner and below said first mentioned flue. 115

6. A heater for driers and the like, comprising a burner casing, a pair of flues communicating at one end with the burner casing, a return flue projecting into the casing and having a closed inner end and perforated side walls, a Y coupling connecting 120 the said flues, and a pipe projecting through said Y coupling into the burner casing and communicating with the top of return flue. 125

7. In a drier, the combination of a drying chamber, a burner casing, a heating element in the casing, a flue communicating at one end with the casing, a return flue communicating with the first mentioned flue and the casing, an outlet pipe located adjacent said flues and communicating with the return 130

flue in the burner casing, and an outlet box communicating with the drying chamber and said outlet pipe.

8. In a drier, the combination of a drying chamber, a burner casing, a heating element in the casing, a flue communicating at one end with the casing, a return flue communicating with the first mentioned flue and the casing, an outlet pipe located adjacent said

flues and communicating with the return 10 flue in the burner casing, an outlet box communicating with the drying chamber and said outlet pipe, and a chimney extending above said outlet box and communicating with said outlet pipe. 15

In testimony whereof I affix my signature.

JULIUS JUDELSON.
